Primary Examiner—Ruth McInroy*Attorney, Agent, or Firm*—Sughrue, Mion, Zinn, Macpeak & Seas[57] **CLAIM**

The ornamental design for a hot water vacuum extraction machine, as shown.

DESCRIPTION

FIG. 1 is a front, top and right side perspective view of a hot water vacuum extraction machine showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

FIG. 1

FIG.2

FIG.3

FIG. 4

FIG. 5

FIG. 6

FIG. 7
